UNITED STATES PATENT OFFICE

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed November 14, 1927. Serial No. 233,030.

This invention relates to an attachment for typewriting machines designed to increase its manifolding power at will.

The attachment substantially includes a flat impression strip of relatively hard material snugly held against the conventional rubber platen along the printing line. The strip is stationary relatively to the rotating platen, and furnishes a suitable backing for an extra large number of carbon-copies.

A feature of the invention is the mounting of the strip in such a way that the same may be quickly called into use or removed.

In one form of the invention, the platen-strip or auxiliary platen forms the cross-bar of a bail or swing-frame which is mounted upon the platen-frame for swinging movement in a plane at right angles to the platen-axis. The platen-strip, therefore, may be swung from forward operative to rearward inoperative position, and suitable (spring) means may be provided to detain the same in either place.

The preferred embodiment of the invention, shown to be applied to the platen-carriage of a standard Underwood machine, employs a rigid swing-frame extending substantially the length of the platen and bearing thereagainst, and pivoted at either side upon the side plates of the well-known Underwood platen-frame. The swing-frame, normally in horizontal position, has at its forward end angularly disposed thereon fixed arms extending downwardly towards the typing line adjacent the ends thereof, which arms in turn hold the manifold platen-strip upon the platen. The strip is preferably made of thin flexible spring metal which has a natural set in the form of a slight bulging

towards the platen from end to end, so that the strip, which in cross-section also conforms to the curvature of the platen, will assume uniform bearing against the platen-surface upon engagement therewith. When the hard platen-surface is not desired, it is swung away from the platen so as not to impede the action thereof. The auxiliary platen, moreover, has a smooth rear face, which, when in use, bears against the platen, but does not prevent the proper step-by-step rotation of

the platen. A compression-spring is provided at either side of the swing-frame. The springs are enclosed in telescopically co-operating tube members, their arrangement being in the nature of an overthrow device which serves to resiliently hold the strip in forward operative or in remote rearward inoperative position.

A further feature of the present invention resides in the arrangement of the overthrow device for co-operation with the swing-frame, so as to urge the auxiliary platen lightly against the main rotary platen, thus assuring a firm contact with the latter, which will give better typing impressions and makes for quieter operation of the machine by preventing chattering of the auxiliary platen-strip.

Other features and advantages will hereinafter appear.

In the accompanying drawings,

Figure 1 is a part-sectional top view upon a platen and platen-frame, showing the auxiliary platen-strip spring-held in operative position.

Figure 2 is a cross-sectional elevation taken upon Figure 1, and showing the auxiliary platen-strip in forward operative and rearward inoperative positions (the latter indicated in dot and dash).

Figure 3 is a perspective view, substantially showing the parts of Figures 1 and 2, and more clearly showing the novel organization of the auxiliary platen-strip.

Figure 4 shows, broken away, the front part of the strip-carrying spring-bail, the strip being shown as being bulged towards the platen from end to end, to cause the strip to evenly bear throughout its length upon the platen.

A revoluble platen 10 of an Underwood typewriter is journaled in the side plates 11 of a usual platen-frame by means of a platen-shaft 12, which terminates in usual platen-knobs or finger-wheels 13. The platen-frame further includes a usual paper-guide 14, which extends back of the platen and downwardly around the lower part thereof and rigidly interconnects said side plates. A pack of work-sheets 15 interleaved with carbons 16 is shown in Figure 2 as being fed

around the platen by means of pressure feed-rolls 17. The paper passes the typing line where a usual type-bar 18 indicates the printing. A little distance beyond the typing line, the paper is held upon the platen by a releasable roller 19, which is carried by an arm 20, partly shown, and which, as known from the Underwood machine, is usually resiliently mounted upon the platen-frame. A 5 blade or strip 21 is stationarily and displaceably held against the platen at the typing line, to serve as a hard working face for the blows of the type-bars, replacing the ordinary rubber face of the platen, when a relatively 10 large number of carbon-copies is to be accommodated. The displaceable platen-strip forms part of a novel organization constituting a swing-frame or bail-member 22, which, by means of brackets 23, is mounted 15 upon the platen-frame and allows the platen-strip to be readily placed in operative or out of the way (inoperative) position. Each of 20 said brackets 23 includes a flat body-member 24 fixed upon flanges 25 forming the top of 25 the side plates 11 by means of screws 26, and which body-members have struck-up ears 27 upon which are rigidly fixed pivots 28 to receive the swing-frame or bail-member 22. Each pivot 28 has a reduced end 29 which 30 passes through an opening in one of said ears 27, the projecting tip of said reduced end being riveted over upon the ear so as to rigidly 35 anchor the pivot thereon. The swing-frame or bail-member 22 includes side arms 30 having hubs 31 which fit over said pivots and which are secured thereon by the heads 32 of screws 33, which are centrally threaded into the free ends of said pivots. The side arms 40 at their forward ends (see Figure 3) have 45 sidewardly and inwardly bent-over parts 34, which, by means of a flat cross-bar 35 and screws 36, are interconnected to create a rigid frame, said bent-over parts further in each case having a depending arm 37 offset 50 from the side arm 30 to clear the side plate 11 and rising curved projections 37^a to serve as finger-pieces in operating the swing-frame. The depending arms 37 extend as far as the 55 typing line and support, fastened thereto by screws 38, said platen-strip 21 proper, which is shown in cross-section to conform to the curvature of the platen. The platen-strip is preferably made of spring-material and formed with a slight bow or natural set towards the platen from end to end so as to assume uniform bearing upon the platen-surface when engaged therewith.

In order to hold the strip or blade 21 in close relation with the platen, there are provided spring-thrust links 38^a, one for each arm of the bail. These spring-thrust links are bipartite, one part being of smaller cross-section than the other part, so as to telescope into the latter. The parts 39 of the links are 65 pivoted by means of pins 40 to upward ex-

tensions 40^a of said ears 27 above the pivot-axis of the corresponding side arms 30. The other half-links 41 are pivoted to the corresponding arms 30 at points adjacent to the crossbar 35 of the bail-member 22. Within 70 the hollow interior of each of the links, there is provided a compression-spring 42 which normally tends to force the halves of the links away from each other, thus snugly forcing said strip 21 against the platen without, however, unduly braking the same, or interfering with insertion of the work-sheets. When the platen-strip 21 is held in operative position along the typing line, as shown in Figure 2, it serves as a suitable backing for the above-mentioned pack of work-sheets and interleaved carbons, in that the imprint of the type-bar 18 will more clearly and distinctly 75 reach the lowermost work-sheet, while the paper-pack, in itself, offers sufficient cushioning to the blow. When a plain work-sheet or a few copies only are to be written, which do not offer any sufficient cushioning effect to the blows of the type-bars, the platen-strip 21 will be displaced by swinging the bail backwardly 80 (see Figure 2) into dot-and-dash position, where it is equally held in place by the over-throw action of said compression-springs 42, thus exposing the surface of the usual hard rubber platen 10 directly as a cushion to the 85 typeblows.

From the foregoing, it will be seen that the present arrangement of the platen-strip allows the operator to quickly engage the same against the platen or to displace it, when not to be used, to a location not interfering with the general operation of the machine, and also over prior detachable devices, eliminates the 90 possibilities of mislaying or losing the same.

Variations may be resorted to within the 95 scope of the invention, and portions of the improvements may be used without others.

Having thus described my invention, I claim:

1. In a typewriting machine having a 100 rotary platen journaled in a platen-frame, the combination of an auxiliary platen of suitable blade-like material set against the rotary platen longitudinally thereof at the 105 typing line while substantially extending the length of the rotary platen and transversely conforming to its curvature, supporting members at the ends of said auxiliary platen for holding it in place stationary 110 relatively to the rotary platen, said supporting members pivoted upon the platen-frame to allow the auxiliary platen to be swung to 115 operative or inoperative position, a bar rigidly interconnecting said supporting members intermediately of said auxiliary platen and the pivot-axis of said supporting members 120 so as to create a rigid frame-structure which positively locates the auxiliary platen upon the rotary platen, and means to resiliently hold the auxiliary platen in either position. 125

2. In a typewriting machine having a rotary platen journaled in a platen-frame, the combination of an impression-strip of harder material set against the rotary platen longitudinally thereof at the typing line and substantially extending the length of the rotary platen, a horizontal frame or bail of flat material pivoted at the rear upon the sides of the platen-frame, depending flat arms extending from said bail at either side thereof to adjacent the typing line and carrying rigidly fastened thereon said strip, the so-formed angular frame-structure swingable from forward operative to rearward inoperative position, stops to limit the rearward throw of the bail, and spring-thrust means to resiliently hold the same in either position.

3. In a typewriting machine having a rotary platen journaled in a platen-frame, the combination of an impression-strip of harder material set against the rotary platen longitudinally thereof at the typing line and substantially extending the length of the rotary platen, a horizontal frame or bail of flat material pivoted at the rear upon the sides of the platen-frame, depending flat arms extending from said bail at either side thereof to adjacent the typing line and carrying rigidly fastened thereon said strip, the so-formed angular frame-structure swingable from forward operative to rearward inoperative position, stops upon the platen-frame to limit the rearward throw of the bail, and spring-thrust means to resiliently hold the frame-structure in either position, said means being in the form of an overthrow spring between each side arm of the swing-frame and the corresponding side of the platen-frame.

40 4. In a typewriting machine having a rotary platen journaled in a platen-frame, the combination of an impression-strip of harder material set against the rotary platen longitudinally thereof at the typing line and substantially extending the length of the rotary platen, a horizontal frame or bail of flat material pivoted at the rear upon the sides of the platen-frame, depending flat arms extending from said bail at either side thereof to adjacent the typing line and carrying rigidly fastened thereon said strip, the so-formed angular frame-structure swingable from forward operative to rearward inoperative position, stops upon the platen-frame to limit the rearward throw of the bail, and spring-thrust means to resiliently hold the frame-structure in either position, said means including compression-springs between each side arm of the respective sides of the platen-frame, said springs being enclosed in telescopically co-operating thrust-members.

5. In a typewriting machine having a rotary platen journaled in the side plates of a platen-frame, a displaceable impression-strip in the form of an attachment, said at-

80 tachment including a frame-structure extending from side to side of the platen-frame, brackets mounted upon the sides of the platen-frame to carry pivoted thereon said frame-structure which forms the support for said strip, and, in its forward operative position, locates the same to contact the rotary platen at the typing line, said frame-structure swingable to rearward inoperative position to displace the strip, stops to determine the rearward throw of the frame-structure, and spring-thrust means in the form of overthrow springs between the brackets and the sides of the frame-structure to resiliently hold the frame-structure in operative or inoperative position.
